C. W. CANINE

LAUNDRY TAG

Filed July 18, 1927

Fig. 2.

Inventor
Chester W. Canine
by Orwig & Hague Attorneys.

UNITED STATES PATENT OFFICE.

CHESTER W. CANINE, OF CINCINNATI, OHIO.

LAUNDRY TAG.

Application filed July 18, 1927. Serial No. 206,523.

The object of my invention is to provide a laundry tag of simple, durable and inexpensive construction, which may be readily, quickly and easily attached to or detached 5 from laundry articles by the use of the operator's fingers only; and also to provide a tag of this character which may be used just as effectively on relatively thin laundry articles as it can on relatively thick ones.

10 A further object is to provide a laundry tag which cannot become detached from the laundry articles in the ordinary process of laundering, and which will not tear or mutilate the most delicate laundry articles, and

15 which can be run through laundry ironing machines while attached to the garment without injury to the tag, the garment or the ironing machine.

A further object is to provide a tag of this 20 character in which, during the washing process, the washing liquid will have free access to every particle of the garment, including that part contained between the flat jaws of the tag, so that portions of the garment contained 25 in the tag are washed just as thoroughly as all other portions of it.

My invention consists in the construction, arrangement and combination of the various 30 parts of the device, whereby the objects contemplated are attained, as hereinafter more fully set forth, pointed out in my claims, and illustrated in the accompanying drawings, in which:

Figure 1 shows a front elevation of a laundry 35 dry tag embodying my invention and attached to a portion of a laundry article, and in closed position.

Figure 2 shows a similar view with the tag 40 in open position ready for removal from the garment.

Figure 3 shows a longitudinal, sectional view on the line 3—3 of Figure 1.

Figure 4 shows an edge view of the tag 45 with the jaws separated by the guiding and locking pin; and

Figure 5 shows an enlarged, detail, sectional view on the line 5—5 of Figure 3.

Referring to the accompanying drawings, it will be seen that the tag is composed primarily 50 of two pieces of spring sheet metal. The one containing the pins is for convenience herein referred to as the lower member, and the one containing the pin openings as the upper member. The lower member comprises 55 a flat, substantially rectangular, body portion 10 and a jaw member 11, all formed

complete of a single piece of spring sheet metal. The body portion 10 is substantially flat and between the body portion and jaw there is an inclined portion 12, which extends 60 from the body portion downwardly and toward the jaw member, and is clearly shown in Figure 4. From the part 12 the jaw member inclines upwardly toward its outer end. In the central portion of the body 10 is a 65 rectangular opening 13, and between said opening and the inclined portion 12 there is a round hole 14, the upper edge of which is beveled or inclined outwardly at 15, as shown in Figure 5. On a central longitudinal plane 70 through the jaw portion 11 there is a series of pins 16 riveted to the jaw portion 11 and having their pointed ends extended upwardly. The length of these pins varies from a minimum at the outer end of the jaw to a maximum 75 toward the body portion, for purposes hereinafter made clear.

The upper tag member is of the same general outline as the lower one and is also made of a single piece of spring sheet metal. 80 It comprises a body portion 17 having a rectangular opening 18 therein, an inclined portion 19 and a jaw 20. The inclined portion 19 extends from the body portion upwardly and toward the jaw portion, and the jaw portion 20 extends from the inclined portion 19 downwardly and toward the outer end of the jaw member. In the jaw member 20 there is a series of openings 21 designed to receive the points of the pins 16. In the body portion 90 17, between the opening 18 and the inclined portion 19, there is a guiding and locking pin 22 riveted to the body portion 17 and having its lower end projected below said body portion and tapered downwardly and 95 inwardly at 23, as shown in Figure 5, and capable of entering the inclined portion 15 of the opening 14 in the lower body portion 10.

The two body portions 10 and 17 are connected by a rivet 24, which rivet is designed 100 to permit the two members to swing relative to each other, but it tends at all times to hold the two body portions in parallel positions. By this arrangement, in order to separate the outer ends of the jaw portions, the material 105 of the two members must be sprung apart and this springing quality tends at all times to hold the outer ends of the two jaw portions together.

110 On the upper face of the body portion 11 there is preferably provided an identification

symbol, such for instance as the numeral 25. When the two tag members are in their normal positions, as shown in Figure 1, the parts are under little, or no, tension because the 5 guiding and locking pin 22 is in the opening 14 and the pins 16 are in the openings 21, and the outer ends of the jaws are in engagement with each other. When in this position, it is obvious that the upper jaw cannot be moved 10 laterally relative to the lower one on account of the locking pin 22. When there is a relatively thin laundry article between the jaws, when they are in their closed position, this article is held firmly within the grasp of the 15 jaws, because it slightly spreads the lower ends of the jaws and there is a yielding spring contact at this point. Furthermore, the numerous pin points 16 penetrate the fabric and because of the coaction of the spring pressure 20 upon the garment and the penetrating pins through the garment, the tag is firmly held to the garment and cannot be removed therefrom by any of the ordinary things that are likely to occur in a laundry operation. One 25 of the reasons why the jaws cannot be accidentally separated in a laundry operation is that the two springing plates are of the same exterior contour and have no sharp corners that are likely to become caught or entangled, and there is nothing in a laundrying 30 process which would operate to first force the jaws apart against the spring pressure to withdraw the locking pin 22 from the hole 14 and at the same time move one jaw laterally on the pivot 24 relative to the other, and both of these operations must be carried on simultaneously in order to detach the tag from the garment.

When a relatively thick garment is placed 40 between the jaws, then the jaws are held slightly further apart, but even in this case the pins penetrate the garment and the fabric is prevented from sliding over the ends of the pins by the upper jaw, into which the 45 pins 16, or some of them, penetrate even the very thickest garments.

By having the pins of various lengths, the 50 points of all of them will penetrate very thin garments and also enter all of the openings in the upper jaw, and it is in the very thin garments that there is always more danger of tearing the material, whereas in relatively thick garments the outer ends of the jaws may be spread so that the shorter pins do not enter the corresponding opening in the upper 55 jaw member, but the longer pins will then pass through the garment and into the opening in the upper jaw member, and there will be more spring pressure applied by the tag to hold the garment in place. Hence, the device 60 operates efficiently to hold it firmly to the garment without danger of tearing the garment, either with very thin and delicate fabrics or with relatively thick and heavy ones.

65 In practical operation, I provide a series of

tags having the same identification mark for the laundry articles belonging to each individual. Then the operator takes each laundry article belonging to a certain individual and opens the spring jaws by forcing the 70 thumb nail into the space between the inclined portions 12 and 19, thus separating the spring jaws and moving the guiding and locking pin 22 out of its opening 15. When this is done, the two jaw members may be 75 readily sprung apart until they reach the position shown in Figure 2, whereupon the garment is placed upon the row of pins 16, after which the upper member is swung back on the pivot 24 to position overlapping the lower 80 member. During this swinging movement, the upper jaw portion is held away from contact with the pin points, by the guiding and locking pin 22, and only when the parts have 85 reach overlapping positions does the pin 22 enter the opening 14, and thus permit the jaws to come together with the pin points 16 entering the openings 21, and when in this position, the garment is firmly clamped between the 90 jaws.

The openings 13 and 18 are provided in the body portion so that these tags may be used in an assorting apparatus and the garments and tags jointly suspended from a rod received in the said openings.

95 I claim as my invention:

1. A laundry tag formed of two members, each comprising a body portion and a jaw portion, means for pivotally connecting the body portions, the portions of the jaw members that are near the body portions being widely separated and the ends of the jaw portions being close together, one jaw portion being formed with an opening, a pin on the other jaw portion to enter said opening when the jaws are in position for engaging the garment, and a locking pin carried by one of the body portions, the other body portion being formed with an opening to receive it, said parts being so arranged that the locking pin will hold the jaws spaced apart at all times throughout the pivotal movement except when the locking pin enters its opening.

100 2. An improved laundry tag comprising in combination two spring metal members, each comprising a body portion and a jaw portion, the body portions being substantially flat and formed with a central opening to receive a bar for supporting the tag, the jaw portions being extended from the body portion first outwardly away from each other and then toward each other at the outer ends of the jaw portions, a rivet for pivotally connecting the body portions together, said parts being so arranged that the ends of the jaws are yieldingly held toward each other by the springing action of the two members held together by the rivet, one of the jaw members being 105 formed with a series of pin openings, and a series of pins fixed to the other jaw member 110.

and designed to enter said openings when the outer ends of the jaw members are adjacent to each other, and a guiding and locking pin fixed to one of the body portions, the other body portion being formed with an opening to receive it, said guiding and locking pin being so constructed and arranged that when it is in its opening the ends of the jaws are brought into position in engagement with each other, and when the guiding and locking pin is in any other position of its movement, it will hold the body portions spaced apart far enough to prevent the jaw having the opening therein from touching the ends of the pin points, substantially as and for the purposes stated.

3. A laundry tag comprising two members,

each having a jaw portion, a pin carried by one jaw and the other jaw being formed with an opening to receive the pin when the jaws are in overlapping positions, means for pivotally connecting the members to permit them to slide over each other from overlapping positions to position with the jaws spread apart in non-overlapping positions, and a locking device on one of the members to coact with an opening formed in the other member and shaped to hold one of the jaws out of contact with the pin on the other jaw at all times during the pivotal movement of the jaw except when the said pin and opening are in alignment.

CHESTER W. CANINE.
